UNITED STATES PATENT OFFICE.

CHILION M. FARRAR, OF BUFFALO, NEW YORK.

DESIGN FOR STEAM-ENGINES.

Specification forming part of Design No. 5,146, dated August 1, 1871.

To all whom it may concern:

Be it known that I, CHILION M. FARRAR, of Buffalo, in the county of Erie and State of New York, have invented and produced a new and original Design for a Steam-Engine, of which the following is a specification:

Figure 1 is a side elevation, showing the shape or form of the frame and the lower part of the cylinder. Fig. 2 represents a front view of the frame; Fig. 3, a plan or top view.

The nature of my design is fully represented in the accompanying drawing, to which reference is made.

I claim as my invention—

The design for a steam-engine, substantially as shown.

CHILION M. FARRAR.
